(57) CLAIM

The ornamental design for a bottle gift set, as shown and described.

DESCRIPTION

FIG. 1 is a perspective view of a bottle gift set;
FIG. 2 is a front elevated view of the bottle gift set of FIG. 1;
FIG. 3 is a rear elevated view of the bottle gift set of FIG. 1;
FIG. 4 is a left side elevated view of the bottle gift set of FIG. 1;
FIG. 5 is a right side elevated view of the bottle gift set of FIG. 1;
FIG. 6 is a top plan view of the bottle gift set of FIG. 1; and,
FIG. 7 is a bottom plan view of the bottle gift set of FIG. 1. The broken lines in the drawings indicated by a “dash-dash” pattern depict portions of the bottle gift set that form no part of the claimed design. The broken lines in the drawings indicated by a “dash-dot-dot” pattern depict a border of the claimed design that forms no part of the claimed design.

The broken lines in the drawings indicated by a “dash-dot-dot” pattern depict a border of the claimed design that forms no part of the claimed design.
